PROCESS FOR THE GASIFICATION OF FINE GRAINED OR PULVERULENT FUELS

Paul Schmalfeld, Bad Homburg vor der Höhe, and Friedrich Danulat, Frankfurt am Main Eschersheim, Germany, assignors to Metallgesellschaft Aktiengesellschaft, Frankfurt am Main, Germany, a corporation of Germany

Application July 22, 1950, Serial No. 175,344

Claims priority, application Germany August 3, 1949

11 Claims. (Cl. 202—14)

This invention relates to a process for the degasification of fine-grained or pulverulent fuels or the like.

It is known to heat pulverulent fuels in externally heated retorts in the absence of air, for the purpose of coking said fuels, while recovering gas, tar and coke. The fuels may be quiescent in the retorts, or they may be moved in or through the retorts mechanically or by their own gravity or by a carrier gas. It is also known to heat and coke pulverulent fuels directly by means of hot gases, either in suspension or in a loose mass agitated by the hot gas (fluidised bed). Direct heating of fine-grained fuels for degasification has also been carried out by means of fine-grained solid heat carriers. Thus, fine oil shale has been blown into a retort by means of steam along with heated fine shale residue, and has been maintained in the retort, by the steam in an agitated mass (fluidised bed). The fine shale residue heated in a separate chamber supplies the heat for degasification (E. V. Murphree, "Gas, Coal, Oil Shale," The Oil and Gas Journal of 8. 4. 1948, p. 69).

All these known processes suffer from certain disadvantages which, in the case of quiescent disposition of the pulverulent fuel to be treated, reside in an inadequate specific efficiency and in the case of material in motion, in the considerable entrainment of dust into the outgoing degasification gas, and also in the dilution of the degasification gas, by the carrier gas.

A process has also been proposed in which a coarse-grained or lumpy solid heat carrier supplies the heat for degasification. In this case, the heat carrier, after being heated in a separate chamber, is mixed with the fine-grained fuel and conveyed through a rotary drum which acts as a degasification chamber. The process was used for degasifying caking coal for the production of predominantly fine coke. After separation of the coke, the heat carrier was elevated, heated up and returned for degasification (Adolf Thau, "Die Schwellung von Braunkohle und Steinkohle"—"The low-temperature carbonisation of brown coal and pit coal"—Halle, 1927, pp. 685 et seq.).

This process requires a considerable number of mechanical devices and has an unfavourable heat exchange between heat carrier and the fuel to be degasified.

The process according to the invention operates with fine-grained or pulverulent solid heat carriers, utilises their favourable heat transfer in the degasification of fine-grained or pulverulent fuels or the like and nevertheless results in a degasification gas which is substantially free from dust.

According to the present invention, the heated fine-grained or pulverulent heat carriers, together with fine-grained or pulverulent fuels or the like, are passed, preferably by their own weight, in the form of a substantially closed downwardly moving charge, through the degasification chamber in such a manner that, at the degasification zone, a free surface of the charge is formed or provision is made in some other way for undisturbed escape of the gas from the charge.

2

The expression "passing a substantially closed charge through the chamber" means a movement of the material of the charge in such a manner that the particles of the material follow each other without essential interstices or that the particles touch each other. The expression free surface or such similar term as used herein is intended to include a large single free surface such as an open top surface or surface of banked material as well as the aggregate of multiple relatively small individual free surfaces such as may be established by the apertures of screens, sieves, or perforated elements of conventional type.

Fuel and heat carrier are preferably mixed together before or at the entry into the degasification chamber.

15 Due to the intimate contact of the dust to be degasified with the hot heat carrier, the dust or pulverulent fuel is rapidly heated and gives off its volatile constituents, gas, tar and distillation liquor, according to the temperature to which it is heated.

20 Since there is no need to use any carrier gas in the process of the present invention, the degasification gas is able to leave the charge undiluted. The smaller quantity of gas permits a lower gas velocity, which prevents or diminishes the blowing up of the charge at the

25 points of escape. A further safe guard against the entrainment of dust by the gas formed during degasification may be attained by making the escape surfaces of the gas from the downwardly moving fuel charge correspondingly large. These escape surfaces may be formed for example by providing free bank surfaces of the charge, or by using louvres, sieves, gratings or the like as retaining walls for the descending charge of fuel and heat carrier. The degasification gas may then be collected in a gas chamber without entrainment of dust and led away, for example, to a cooling, condensation and scrubbing apparatus. The intimate contact of the dust or powder with the hot heat carrier results in a high specific efficiency of the apparatus.

30 In the herein described process, for example, a fine-grained or pulverulent heat carrier is used which, with suitable material to be degasified, conveniently consists of the coke or residues formed in the degasification. After withdrawal from the degasification chamber the mixture of circulating heat carrier and newly formed coke or residue, which is likewise used in fine-grained or pulverulent form, is elevated pneumatically by means of air and if desired with the addition of other gases, with simultaneous heating, preferably by the reaction of the conveying air with carbon contained in the residue.

35 Depending upon temperature conditions and reaction velocities, the reaction results in varying ratios of carbon dioxide to carbon monoxide in the reaction gases of the conveying air.

40 The heat carrier, after being heated up, is separated 45 in a separator from the reaction gases of the conveying air and is returned to the degasification chamber. Advantageously, the separator is one primarily for coarse particles for example in the form of a settling chamber or a simple cyclone, so that the finest fractions are separated only to a limited extent and are led out of the heat carrier circuit together with the reaction gases.

45 If the coke produced or its ash does not possess an adequate granular form, i. e. if it is for example, too fine, it is possible to employ as heat carrier, for example, other fuel ashes, chamotte, alumina, silica (quartz or other modifications), silicates, magnesium oxides or the like, or mixtures thereof. The heat carrier should preferably not tend to deteriorate excessively such as by splintering, abrasion, chemical reaction or the like, so that the amount required and the production of fine dust will not increase excessively. If desired it is possible to use an extraneous

heat carrier in addition to the residue of the degasification material.

The grain of the circulation heat carrier preferably lies between about 0.1 and 1.0 mm. diameter. If the grain is finer than 0.1 mm. separation from the conveying gases is generally more difficult and requires separators for fines operating at a higher gas velocity and hence with a higher power consumption due to the necessarily incurred pressure loss. On the other hand, the velocity necessary for maintaining suspension increases with the grain diameter, so that the velocities required for the pneumatic conveying and hence the power consumption and deterioration increase with the grain diameter, and at substantially greater diameters than 1.0 mm. the costs of the process may increase to render the same uneconomical.

Preferably, the fuel introduced has likewise a maximum grain size of 1.0 mm. It may, however, also be somewhat coarser, since shrinkage or diminution of the specific gravity of the grain occurs through the degasification process. The advantageous grain size of the fuel can readily be attained by screening, or if coarse grain is supplied, it can readily be produced by simple pulverising, and does not require any high grinding costs, such as is frequently the case in normal pulverised fuel firing or dust gasification, owing to the requirement for a very finely ground powder.

The circulation of the heat carrier is regulated so that the latter, together with the material to be degasified, moves in a closed charge through the degasification chamber, the latter being closed from the conveyer chamber and separation chamber preferably by the charge. This is achieved, for example, by providing below the degasification chamber, a throttle device which allows to adjust the quantity of the mixture of heat carrier and residue leaving the degasification chamber. In particular, if care is taken to ensure that the mixture of heat carrier and degasification material is introduced into the degasification chamber in a closed charge, a further result of the throttling is that there is a closed column of material in the degasification chamber. The height of the column of material is determined, for example, by an overflow, through which excess of heat carrier is removed before the supply of fresh material to be degasified enters. On its passage through the degasification chamber, the heat carrier is increased by the degasification residue.

After pneumatic conveying, the most finely granular fraction is partly separated. The heated heat carrier, together with the freshly supplied fuel, then forms the charge and the excess flows away through the overflow. If no excess remains, because the proportions of fine dust being removed is greater than the supply of degasification residue, additional heat carrier is preferably introduced into the cycle so as to maintain a closed charge. This may be effected, for example, together with the material to be degasified. The closed column of material from the throttle device to the overflow prevents flow of gas between the gas chamber of the degasification chamber on the one hand and the conveyor chamber or separation chamber on the other. Preferably, the pressure in the degasification chamber is maintained in constant dependence upon the pressure in the pneumatic conveying chamber. E. g. there should be maintained in the separation chamber of the separator a suitable excess pressure relative to the pressure in the degasification chamber.

The quantity of conveyor air determines the heat supplied to the heat carrier by reaction of the conveyor air with the carbon in the residue. If the air required for combustion is insufficient for carrying out the conveying of the heat carrier, other gases not participating in the reaction are preferably added, such as for example combustion gases or even nitrogen. If the heat carriers removed from the overflow shall be substantially free of

carbon, steam, if desired also carbon dioxide or even both, may be mixed additionally with the conveyor air. Any carbon of the residue which is not consumed in the heating is thereby converted into carbon monoxide

5 and hydrogen. This is particularly advantageous if the conveyor gases are further used after leaving the pneumatic conveying and separation of the circulating heat carrier. The said gases may, for example, be supplied directly to a steam boiler connected in line. Secondary 10 air is blown into the steam boiler to burn up completely the combustible components of the reaction gases and of the fine dust carried along with them.

This method of carrying out the herein-described process has the advantage that the supplied material to be 15 degasified is converted completely into concentrated degasification gas, weak gas and fine dust in a highly heated form. The process may thus advantageously be combined with pulverised fuel firing installations, for example in steam boilers, for producing concentrated degasification gas, for example for town gas purposes, and liquid hydrocarbons, and for converting the residual coke into producer gas and dust of the very finest form at a high temperature, which in this form may be used with great advantage for firing steam boilers. The process may, 20 however, also be employed with great success, for example in combination with roasting and sintering furnaces or other metallurgical processes. The utilisation of the sensible and chemically combined heat of the conveyor gases and entrained fine dust is also effected, preferably 25 in a steam boiler or the like, if the carbon of the degasification residue has not been completely gasified, but a portion is removed as granular residue at the overflow duct.

In cases where the fine dust is troublesome in the combustion of the reaction gases in the steam boiler or other devices, since it may tend to produce deposits and cause considerable wear, the gases may be substantially freed from dust by separators for removal of fines for example 30 in the form of highly effective multiclones. As a result of the fine dust removal, higher gas velocities may be used in the steam boiler, or even for example in a gas turbine. The separated fine dust is then used for the heat carrier circuit or for other purposes, for example it is supplied to a separate steam boiler, a sintering apparatus 35 or the like for utilising the carbon contained therein.

The degasification may be carried out according to choice at high, medium or even low temperatures. This mainly depends upon the desired nature of the degasification products. If a high degasification temperature, for 40 example 1000° C. is used, the tar liberated from the degasification material is decomposed to a considerable extent and converted into gas, and the volatile constituents of the degasification material are expelled to a considerable extent. In this case, only a small quantity of coke 45 remains as residue. If, on the other hand, degasification is carried out at low temperature, for example 600° C. the tar liberated from the degasification material is extensively preserved and leaves the degasification chamber together with the degasification gas. The quantity of 50 degasification gas is less than in the case of high temperature degasification, but in general the gas has a higher calorific value; the quantity of the residue is also greater, since a portion of the volatile constituents remains in the coke. If, when working at low temperatures, it is desired substantially to avoid the consumption of coke for 55 heating the heat carrier, heating gases may advantageously be added to the conveyor air for supplying the necessary quantity of heat for heating the heat carrier by combustion of the heating gases.

In some cases, it may be desirable to add water gas to the degasification gas, for example in order to increase the quantity of gas or also to reduce the calorific value of the gas, so that the mixed gas satisfies, for example, the standards for town gas. The production of water gas may be combined with the degasification, for example by

introducing steam into the lower part of the degasification chamber and allowing it to pass through the chamber charge consisting of a mixture of fuel and circulating heat carrier of high temperature. The steam reacts partly with the carbon of the fuel, and by dissociation in accordance with the equilibrium conditions produces mainly carbon monoxide and hydrogen, together with certain quantities of carbon dioxide. Adjustment of the calorific value of the gas may also be effected by other means, for example by injecting together with the steam or instead of steam, air, oxygen or oxygen-enriched air or the like. The injection of steam or the like and the production of water gas increase the quantity of gas passing through the charge, so that a corresponding entrainment of dust may be expected. Preferably, therefore, the water gas is produced in a separate apparatus, or in a chamber connected in series with the degasification chamber and is added to the degasification gas only after it has been cleaned.

If the recovery of the tar contained in the fuel is to be as complete as possible, which is above all attainable by using low degasification temperatures and avoiding decomposition, the introduction of small quantities of scavenging gases e. g. steam or combustible gas into the degasification chamber may be of advantage, so that by a scavenging effect, a more rapid removal of the tar vapours is obtained, thus preventing as far as possible, the decomposition of the tar. In doing this, care should be taken to avoid as far as possible any eddying or whirling up of the dust.

From the point of view of heat economy, it is of advantage to preheat the air for the pneumatic conveying of the circulating heat carrier and/or the freshly supplied fuel. It is advantageous to utilise the heat of the degasification gas discharged in the hot condition or of the reaction gas or gases, after the separation of the circulating heat carrier, for heating the air and/or the fuel, in which case, the fuel may be previously dried and also, if necessary, its caking tendencies may be previously removed by a thermal treatment.

The fresh material to be supplied and degasified is preferably uniformly and intimately mixed with the heated heat carrier. Preferably, this is carried out in an apparatus through which the heated heat carrier passes in a thin stream and at a correspondingly high velocity, the fresh fuel being fed into the stream at the same time in a uniform and steady manner. For example, about three to twenty times, and preferably by nine to twelve times the quantity by weight of heat carrier to fresh material is employed relatively to the quantity of fresh fuel, so that the individual fuel grains are well enveloped and rapidly heated. In consequence of the fuel being made lean by the circulating heat carrier, the rapid movement at the inlet to the degasification chamber and the rapid heating, there is no appreciable caking together or even lump formation in the case of caking fuels, so that all fuels may be used, irrespective of their caking tendencies. Any caking together of a few individual grains is harmless and is, for the greater part, destroyed in the pneumatic conveyor duct.

Preferably, the process of the present invention is carried out in an apparatus in which the separating chamber for the heated heat carrier is situated above a degasification chamber and is connected to the latter by a preferably narrow shaft for the supply of the heated heat carrier. The conveying path for pneumatic conveying is preferably situated in the interior of the apparatus so that it passes through the degasification chamber, the supply channel for the mixture of heat carrier and material to be degasified and the separating chamber for the heat carrier. It is, however, also possible to arrange the conveying path outside the degasification apparatus.

In order to enable the invention to be more readily understood, reference is made to the accompanying draw-

ing which illustrates diagrammatically and by way of example, one embodiment of apparatus suitable for carrying the herein-described process into practical effect.

Fig. 1 is a vertical section through such an apparatus. Fig. 2 shows some details of this apparatus.

In said drawing, 1 denotes a vertical rectangular or round shaft in which degasification is carried out. 2 is a pneumatic conveying channel, in which the heat carrier is elevated while being simultaneously heated. 3 is the primary separator for separating the heated heat carrier from the gases, and is shown in the form of a settling chamber. 17 is a sheet-metal casing surrounding the apparatus and 18 is a refractory lining. The separator 3 is situated above the degasification chamber 1 and is connected to said chamber 1 by a narrow channel 4, in which the heat carrier, heated to a temperature of about 600 to 1200° C., for example 1000° C., according to requirements, continuously descends into the chamber 1. The channel 4 is shown as an annular space around the conveyor section 2 which passes axially through the degasification chamber 1. The channel 4 may also be formed as an enclosed channel, independent of the conveying channel 2.

The fresh fuel is fed continuously into the channel 4 from a supply container 5. The feeding device in the embodiment shown consists of a casing 21 enclosing the channel 4 above the chamber 1. The supply line 22 of the container 5 discharges into the casing. The casing 21 contains the ring 6 which is arranged and may be rotated in a conventional manner, for instance by means of a gear drive 23. The ring 6 carries the horizontal annular disk 24 above which the fixed shovels 25 are arranged. When setting the ring in rotation, the shovels will convey the charge introduced into the casing 21 by the supply line 22 and carried by the annular disk 24 into the holes or slots 7 through which the charge gets into the channel 4. The shovels 25 are arranged in the casing 21, the holes or slots 7 along the wall of the channel, both at suitable, advantageously equal spaces.

40 The fuel, mixed with the hot heat carrier, rapidly descending through the channel 4 into the degasification chamber and being heated gives off its volatile constituents which ascend in the gas-collecting space 8, and at 45 pass from the degasification chamber, for example to cooling, condensation and scrubbing apparatus of known type not shown in the drawing. The degasified fuel, in mixture with the cooled heat carrier, at a temperature of about 400-1000° C., for example 700° C., according to the selected conditions, descends slowly in chamber 1 and via a throttling device 10, which regulates the circulating quantity of heat carrier, passes laterally into the lower part of the conveying channel 2. Air is introduced from below into the conveying channel 2 via the duct 11, said air being advantageously heated in a superheater 12 to a temperature of about 200 to 1000° C., for example 500° C. The heat exchange may be carried out with the hot degasification gas or the hot combustible gases of the conveyor air or also with any desired extraneous source of heat. The conveyor air supplied takes the heat carrier upward in the conveying channel 2 and reacts with the carbon in the heat carrier, with the formation of carbon dioxide and carbon monoxide and a corresponding evolution of heat, so that the heat carrier is heated to the desired temperature between about 600 and 1200° C., for example to 1000° C. In the separator 3 the coarser grains of the heat carrier are separated from the reaction gases and returned to the degasification chamber 1, thus closing the circuit of the circulating heat carrier. The reaction gases, still charged with the finer grains of dust, leave the separator 3 at 13 and are supplied to a steam boiler 14, in which the reaction gases and dust are completely burned with the addition of air (from the duct 15). Connected to the channel 4 or separator 3, at a point above the feeding device 6, 7 for the fuel, is an overflow duct 16, through which excess of heat carrier, for example

coke is removed from the cycle. In order to ensure satisfactory operation, it is necessary that at least small quantities should be continuously withdrawn from the overflow conduit 16, this being preferably controlled. Withdrawal of heat carrier at the overflow ensures that the channel 4 is continuously filled with heat carrier or fuel, this being necessary in order to obtain a reliable gas seal between the degasification chamber 1 and separator 3, in combination with a suitable pressure regulation in the degasification chamber 1 and the separator 3 in mutual dependence. If the fuel does not form an excess of coke which can be withdrawn from the overflow duct 16, an additional heat carrier is advantageously supplied to the cycle in order to ensure the existence of a closed charge. The heat carrier withdrawn from the overflow conduit 16 may then be returned to the cycle, for example together with the material to be degasified. 19 is a grate arranged in the lower part of the degasification chamber 1, to which steam may be supplied through the pipe line 20 for effecting the formation of water gas in the degasification chamber, or to scavenge the chamber so that degasification gas charged with tar vapours will be withdrawn more rapidly from the chamber.

By means of the aforescribed apparatus, it is possible to carry out the degasification of finely granular or pulverulent fuels.

The process and apparatus of the present invention are particularly adapted for the production of gas of high calorific value, for example, for town gas purposes, or for the recovery of individual gaseous hydrocarbons from the gas or for the recovery of tar in combination with power generation, for which the reaction gases formed with the conveyor air and the fine dust at a high temperature are used with particular advantage. Due to the simplicity of construction and the rapid readiness for operation of the apparatus, the process is to be used with particular advantage for covering peak requirements. For covering special peaks in gas and power requirements, which occur at different times, it is possible preferably to use the tar produced, in addition to adjustment of the working conditions adapted to the necessary requirements. By returning the tar to the degasification chamber and decomposing it, the gas yield may be increased, or the tar may be burned, for example in a steam boiler.

The apparatus is of closed construction and may also be operated at higher pressures, if this should prove desirable in special cases, for example for the better utilisation of hot conveyor gases produced under pressure, for example in gas turbines, or for the production of degasification gas under super-atmospheric pressure, which facilitates cleaning and transport.

What we claim is:

1. In a method for the degasification of normally solid finely divided fuels, the improvement which comprises mixing a heated solid and solid fuel together, said solid being heated to at least the degasification temperature of said fuel, moving the mixture downwardly through a confined feed column, into a closed degasification zone, establishing a free surface of material in the closed degasification zone, moving the mixture downwardly in a non-fluidized bed through said degasification zone, sealing the material feed and discharge from said zone against the passage of gas, removing the solid and fuel residue from the bottom of said zone, removing gas produced from the free surface, elevating solid residue material in a confined zone with a combustion supporting gas, burning a portion of said residue material in said elevating zone, separating the coarse heated solid from the gas and fine material, and returning the coarse heated solid to said mixing step.

2. The improvement according to claim 1 in which

the particle size of at least one of said solid and said fuel is of the order of magnitude not to exceed about 1.0 mm., in which said fuel is fed to said mixing step to maintain for said coarse solid return a ratio of returned solid to fuel of about 3-20:1 by weight, and in which said sealing is accomplished by columns of said residue material.

3. The improvement according to claim 2 in which said returned solid is heated to a temperature of at least 600-1200° C.

4. The improvement according to claim 3 in which said fuel is coal, in which said combustible solid is material derived by the gasification of such coal and in which said mixture is gravitationally moved through said degasification zone.

5. The improvement according to claim 4 in which the particle size of at least one of said fuel and of said solid is of the order of 0.1-1.0 mm.

6. The improvement according to claim 1 in which said sealing is accomplished by columns of residue material of lesser cross-sectional area than that of the mixture passing through said degasification zone, in which said mixture is gravitationally passed through said degasification zone, and in which said fuel is fed to said mixing step to maintain for said coarse solid return a ratio of returned solid to fuel of about 3-20:1 by weight.

7. The improvement according to claim 6 in which said fuel is coal, in which said combustible solid is derived by the degasification of such coal, and in which the

particle size of at least one of said coal and said degasified coal is within the order of magnitude not to exceed about 1.0 mm.

8. The improvement according to claim 7 in which said combustible solid is heated to at least a temperature of 600-1200° C.

9. The improvement according to claim 6 in which said residue material is elevated in a confined zone passing substantially centrally through said mixture and through said sealing columns.

10. The improvement according to claim 1 in which said fuel is fed to said mixing step to maintain for said coarse solid return a ratio of returned solid to fuel of about 3-20:1 by weight.

11. The improvement according to claim 1 in which said sealing is accomplished by columns of said residue material.
